UNITED STATES PATENT OFFICE.

ETHAN I. DODDS, OF CENTRAL VALLEY, NEW YORK.

STEEL TRUCK FOR RAILWAY-CARS.

1,121,552.

Specification of Letters Patent. Patented Dec. 15, 1914.

Application filed March 25, 1908. Serial No. 423,154.

To all whom it may concern:

Be it known that I, ETHAN I. DODDS, a citizen of the United States, residing in Central Valley, in the county of Orange and State of New York, have invented a new and useful Improvement in Steel Trucks for Railway-Cars, of which the following is a specification.

My invention relates to improvements in trucks for rail way cars, and more particularly to improvements in steel trucks of the four wheeled type.

The object of my invention is to provide an all steel four wheeled car truck which will have a certain and proper amount of elasticity to cause it to operate with ease and efficiency, and which will at the same time have great strength and durability, and in which the center plate of the truck will be materially lower than in the constructions heretofore in use, so that the center sills of the car body may be made strong and deep without raising the height of the car body.

My invention consists in the novel construction of parts and devices and in the novel combinations of parts and devices by which this object or result is practically accomplished, the same being more particularly set forth in the claims.

In the accompanying drawing, forming a part of this specification, Figure 1 is a plan view, partly in horizontal section, of a four wheeled steel car truck frame embodying my invention, the wheels, car axles and brake mechanism being removed. Fig. 2 is a side elevation, partly in longitudinal section, on line 2—2 of Fig. 3; and Fig. 3 is an end elevation, partly in transverse section, on line 3—3 of Fig. 2.

In the drawing 1 represents the wheels of a four wheeled car truck, 2 the axles, 3 the coiled springs, 4 the elliptic springs, 5 the journal boxes, 6 the brake shoes, and 7 the brake mechanism, all these parts being of any ordinary or customary construction.

My improved construction of steel car truck frame, comprises in coöperative combination, side frame upper or compression members 8, each composed of a pair of rolled steel channels 9 placed with their webs back to back and connected by interposed connecting castings 10 of cast steel, lower or tension members 11 each composed of a pair of channels 12 placed with the webs back to back and connected by said connecting castings 10. The truck frame

further comprises rolled or pressed steel transoms 13 and connecting castings 14 by which said transoms 13 are connected to the two side frames, and a depressed cast steel bolster 15 having a center plate 16, and extending at its ends 17 over the elliptic springs 4.

The connecting castings 14 are provided with lugs 18 for the suspension of the spring plank 19 through the medium of the forged hangers 20. The pedestals 21 extending between the compression members 8 and the tie members 11 of the side frame are of cast steel.

As clearly shown in Fig. 2 of the drawing, the lugs 18 which are formed integral with the castings 14, are located inside of the transoms 13. The castings 14, as will be obvious, provide an unusually rigid connection between the side frames and the transoms 13.

By this construction and arrangement of parts, the cast steel truck bolster is brought well below the compression members 8 of the truck side frame, so that the car body may have strong and deep center sills without increasing the height of the car, and at the same time the frame as a whole is made exceedingly strong and also given the requisite elasticity to cause it to operate with ease and efficiency and to give it durability. The truck side frames are further connected by angle bar transoms 22 which are secured at their ends to the forged steel safety 90 guards 23.

I claim:

1. A four-wheeled car truck comprising, in combination: side frames having upper compression members and lower tension members; pedestals located at the ends of said compression and tension members and extending therebetween and connecting the same; transoms tying said side frames together; connecting castings, one on each side and located midway the length of said compression and tension members and connected thereto, each of said castings having an integral bolster hanger lug located inside of the transoms; and a truck bolster connected to said lugs and extending from side to side of the car truck, said bolster being depressed below the bottoms of said upper compression members of the truck side frames, substantially as specified.

2. A steel car truck comprising, in combination: side frames, each including an up-

per pressed or rolled steel compression member and a lower pressed or rolled steel tension member; pressed or rolled steel transoms; pedestals extending between and connecting said compression and tension members of said side frames; hangers; springs; a pair of cast steel connecting castings, one on each side frame and located at the longitudinal center thereof for connecting the

transoms to the side frames; and a cast steel truck bolster having a center plate depressed below the bottoms of the upper compression members of said truck side frames, substantially as specified.

ETHAN I. DODDS.
